UNITED STATES PATENT OFFICE.

LIPA POLINKOWSKY, OF NEW YORK, N. Y., ASSIGNOR TO WESTERN ELECTRIC COMPANY, INCORPORATED, OF NEW YORK, N. Y., A CORPORATION OF NEW YORK.

MACHINE-SWITCHING TELEPHONE-EXCHANGE SYSTEM.

Application filed May 21, 1919. Serial No. 298,707.

To all whom it may concern:

- Be it known that I, LIPA POLINKOWSKY, a citizen of Russia, residing at New York, in the county of New York and State of New York, have invented certain new and useful Improvements in Machine-Switching Telephone-Exchange Systems, of which the following is a full, clear, concise, and exact description.
- This invention relates to telephone exchange systems in which machine switching apparatus is used for setting up connections between subscribers' lines.
- More particularly it has to do with a telephone system involving a plurality of exchanges or switching stations provided with interconnecting trunk lines, whereby a subscriber's line terminating in one switching station may be extended by automatic switches therein to an outgoing trunk, and thence over switches in the distant exchange or switching station into connection with a desired line.
- An object of the invention is to provide, in a system of this character where interconnecting trunk circuits are arranged between switching stations, means whereby the subscriber of a line local to one of such stations is enabled to transmit impulses by his sender over a two-conductor impulse transmitting circuit, which is free from impedances, bridges, ground, or other connections, to a distant station to control the setting of selective switches therein.
- A feature of the invention consists in arranging means such that after impulses have been sent from one station over a trunk line to the distant station, and the switches therein have completed their operation in accordance with the designation sent, the impulse transmitting circuit is automatically converted into a talking circuit by connecting a source of talking current thereto at the first station.
- A further feature is the provision of a three-conductor trunk circuit between switching stations, two of which conductors form a circuit for sending impulses directly from the subscriber's line at the first station to a distant station, together with means such that after the switches in the distant station have been operated, a timed control is exer-

cised over the third conductor of the interconnecting trunk circuit to cause the connection of talking battery thereto at the first switching station.

A still further feature consists in the provision of means such that, after the switches in the distant exchange or switching station have been operated, a predetermined time opening of the third conductor of the interconnecting trunk serves to connect in the talking battery at the first station, while the opening of the third conductor for a longer interval brings about the release of the switches at the first switching station.

Such other features as are contemplated by the present invention will become apparent from the following description and appended claims.

In the drawings Fig. 1 shows a subscriber's line leading to a satellite and the detailed circuits of a first line finder switch and a second line finder switch for extending the line to a trunk circuit which leads to a distant exchange. There is also shown in this figure the outgoing end of such a trunk circuit together with means controllable over the trunk from the distant exchange for connecting talking battery to the trunk in the satellite, and for causing the release of the finder switches.

Fig. 2 shows the incoming end of the trunk line at the distant exchange and the circuits of a group selector switch for extending the same to succeeding selector switches to complete the connection with the called subscriber's line.

Figs. 3 and 4 illustrate the circuit arrangement of a register controlling equipment adapted to be set by impulses transmitted from the calling line over the trunk circuit from the satellite to the exchange, for the purpose of controlling the selective operation of the automatic switches.

In reading the drawings, Figs. 1 and 2 should be taken in order from left to right with Fig. 3 below Fig. 2, and Fig. 4 to the left of Fig. 3.

The switches employed in this system may be of the same general construction and operation as the one shown in the patent to McBerty No. 1,097,868, granted May 26, 1914. The controlling sequence switches

and registers are of the same type and construction as the one described in detail in the patent to Reynolds and Baldwin 1,127,808, issued February 9, 1915.

5 It is believed that a more comprehensive understanding of the invention may be given by describing in detail the operation of the system in which the same is embodied in the establishment of a connection from one subscriber's line to another.

10 Assume first that the subscriber at the substation 600 belonging to a satellite or other switching station, desires to obtain a talking connection with a subscriber's line, such as line 650 belonging to a distant exchange or switching station. On removing his receiver from the switchhook, a circuit is established from battery through the left-hand winding of the line relay 604, outer

15 contact and armature of cut-off relay 607, over the loop of the calling line, inner armature and contact of relay 607, through the right-hand winding of relay 604 to ground. The line relay 604, by attracting its armatures, closes a circuit from battery through the inner windings of the common starting relays 605, armature and contact of relay 604 to the multiple terminals 614 of all first line finders having access to the group in

20 which the calling line appears. This causes a selectable potential to be placed upon these multiple terminals to identify the calling line. Upon the energization of the relay 605 a circuit is closed from ground, over the 25 armatures and contacts of these relays, and thence in parallel through the windings of the magnets 606 of all idle first line finders, back contacts and armatures of relays 610, to battery and ground at the contacts and armature of relays 613 of such idle finders.

30 The power magnets 606 cause, in the well-known manner, the rotation of the brush carriage of the line finder switches to search for the calling line. If the test brush of an idle first line finder chances to be in contact with the terminal 614, or as soon as a finder advances its test brush into engagement with such terminal, the selectable condition is found thereon and a circuit is

35 completed through the right-hand high resistance winding of test relay 609, to ground. The relay 609 receives sufficient current to energize in this circuit, and by attracting its armature closes a circuit through its left-

40 hand low resistance winding, and the winding of the second test relay 610 to ground in shunt of its high resistance winding. The resistance of this latter circuit being relatively low, the potential on test terminal

45 614 is sufficiently reduced so that other line finder switches will not stop on the terminals of the calling line. The brush carriage continues to rotate until its brushes are accurately centered upon the terminals of the calling line, at which time the interrupter

50 brush 615 is out of contact with its cooperating segment, and the short circuit around relay 610 being thus removed, said relay energizes. The relay 610, by attracting its armature, opens the circuit of power magnet 70 606 and closes a circuit from battery, armature and contact of relay 613, armature and front contact of relay 610 through the winding of holding magnet 611, through the windings of common starting relays 75 612, to ground. The holding magnet 611 brings the brush carriage to rest. A circuit is also completed from battery, armature and contact of relay 613, armature and front contact of relay 610, to the multiple terminals 80 630 in the second line finder switches, to place a selectable potential thereon.

85 The second line finder switches are arranged in pairs so that when both switches of a pair are idle only one is started in operation upon the initiation of a call. To accomplish this one second line finder switch of each pair is provided with an additional relay 677. The test relay 674 of the other line finder of the pair may be wired so that the connection of its right-hand winding to ground leads over the left-hand armature and contact of relay 677 by way of a lead 619 which may be connected as shown at the cross 616. The leads 617 and 618 may, 90 be connected at the cross 699 in the power circuit of the second line finder switch of the pair, so that such power circuit is normally maintained open at the armature and contact of relay 677. When the finder 100 switch of the pair provided with the relay 677 is busy this relay will be energized, as hereinafter shown, to close the circuit to ground of the right-hand winding of test relay 674 of the other finder switch of the 105 pair, and the right-hand armature of relay 677 closes the break in the power circuit of said other finder switch. In this manner the initiation of a second call during the time the first switch of each pair is busy 110 causes the operation of the second finder switch of each pair.

115 When the starting relays 612 energized, a circuit was closed from battery over the armatures and contacts of these relays in parallel through the power magnets 621 of one idle second line finder switch of each pair, and thence over the back contact and armature of relay 672, right-hand armature and contact of relay 676, to ground at the 120 right-hand armature and back contact of relay 673. The brush carriages of the second line finder switches are thereupon rotated to advance the test brushes over the multiple terminals in search of the connecting circuit leading from the calling first line finder. As soon as the second line finder moves its test brush into engagement with the multiple terminal 630 of this connecting circuit, the selectable condition is found 125 130

thereon and an energizing circuit is completed through the right-hand high resistance winding of test relay 674 to ground, either directly or by way of lead 619 and 5 the left-hand contact and armature of relay 677, dependent upon which finder of the pair is taken for operation. The relay 674 operates and closes a low resistance path to ground through its left-hand winding 10 and the winding of relay 672, thus reducing the potential on the multiple terminals 630. As soon as the brushes are accurately centered, relay 672 energizes and opens the above traced circuit of the power magnet 15 621, thus terminating the movement of the brush carriage. At the same time a circuit is closed from battery through the winding of relay 675, front contact and armature of relay 672, right-hand armature and contact 20 of relay 676, to ground at the right-hand armature and back contact of relay 673. The relay 675 energizes and closes a circuit from battery through the winding of the cut-off relay 607, relay 613, armature and 25 back contact of relay 664, through the winding of relay 673, contact and armature of relay 675, to ground. Relays 607, 630 and 673 are energized whereas the meter magnet 608, which is connected in parallel with 30 the circuit just traced, being marginal, does not operate at this time.

The relay 675 is constructed so as to attract its armature slowly. Should two second line finders stop at the same instant 35 on the terminals of a calling circuit, and test relays 674 become operated, the parallel circuits established to ground through the low resistance relays 672 will not receive a sufficient flow of current for both of the relays 672 to remain energized. Consequently, the relay 672 of one of such finder switches will release its armature to open the circuit of relay 675 before this latter relay has had 40 time to operate and close an energizing circuit for the relay 673, which in turn opens the circuit of the power magnet 621. This finder switch, therefore, continues to rotate 45 without disturbing the calling circuit.

When the cut-off relay 607 energized it 50 opened the circuit of the line relay 604 which released its armature and opened the circuit of the common starting relay 605. These relays, by deenergizing, interrupt the power circuits of magnets 606 to terminate 55 the movement of all other rotating first line finders. The relay 613 by energizing and the test relay 610 by deenergizing at this time open the circuit of the common relays 612, which in turn open the power circuit 60 of all rotating second line finder switches, thus bringing the same to rest.

Relay 673 which, as above noted, is energized in series with relays 607 and 613, 65 closes a holding circuit for itself independent of the relay 675, traceable through the

winding of relay 673, its left-hand contact and armature, back contact and left-hand armature of relay 676 to ground at the front contact and right-hand armature of relay 673. Relay 673 also closes a circuit 70 for the relay 635 which leads from ground over the right-hand armature and front contact of relay 673, armature and back contact of relay 678, through the windings of relays 635 and 677, to battery and ground. 75 Relay 635 at its front contacts closes the normally opened talking conductors at the outgoing end of the trunk circuit which leads from the satellite to the distant exchange. The relay 677, as described, prepares circuits at the other line finder switch of the pair so that the same may now be taken for use in the event that another call is made while the finder switch shown is 80 busy.

The relay 635 having closed the two conductors of the calling subscribers' lines directly through to the distant exchange shown in Fig. 2, a circuit is established for the relay 622. This circuit leads from battery through the winding of said relay, contact 632 (1) of sequence switch 620, trunk conductor 655, right-hand armature and front contact of relay 635, thence over the loop of the subscriber's line 600, and returning through the front contact and left-hand armature of relay 635, trunk conductor 654, sequence switch contact 642 (1), home contact and interrupter brush 652, through the winding of the relay 638, to ground. When the relay 622 energizes, a circuit is closed from battery, through the winding of the sequence switch magnet 620, contact 647 (1), front contact and armature of relay 622, to ground at the armature of relay 631. Sequence switch 620 leaves position 1 and moves into position 4. As the sequence switch 620 reaches position 3, a circuit is closed from ground, over the armature and contact of relay 663, sequence switch contact 636 (3 to 13), left-hand armature and back contact of relay 624, third conductor 603 of the trunk circuit through the windings of relays 670 and 664, to battery and ground. Relay 670 energized but relay 664 being of the marginal type remains inert at this time. A circuit is thereupon closed in the satellite from battery, armature and front contact of relay 670, through the winding of the slow-to-release relay 671, to ground, at the back contact and armature of relay 671, and also to ground, through the right-hand winding or slow-to-release relay 676. The relay 671 operates and completes a circuit at its armature and front contact to hold the relay 673 energized before the circuit which is now holding relay 673 can be opened at the back contact and left-hand armature of relay 676, which latter relay, it will be observed, attracts 115 120 125 130

its armatures as soon as the relay 671 removes the shunt from around the right-hand winding of such relay 676. As soon as the relay 676 operates, it closes a holding circuit over its left-hand winding, front contact and left-hand armature to ground at the front contact and right-hand armature of relay 673. The circuits in the satellite remain in this condition until the 10 switches at the exchange have completed their operation.

As the sequence switch 620 reaches position 3 and also in position 4 thereof, battery current is connected in bridge of the 15 calling line through the windings of relay 631 and retardation coil 623 by the closure of sequence switch contacts 601 and 602. In position 4 of sequence switch 620, the selection of an idle registering mechanism 20 takes place. For this purpose a testing sequence switch 680 is provided to test the idle or busy condition of the register mechanisms, and upon finding an idle one, associates the same with the incoming end of the 25 trunk line over which a call has been extended. The circuit for initiating the testing operation of sequence switch 680 extends from battery, through the winding of the magnet of said sequence switch, contact 643 (4), back contact and armature of relay 638, which relay is now deenergized, contact 654 (4), contact 655 of sequence switch 680, closed in the consecutive positions 1 to 9, to ground. When an idle register controlling mechanism is found, a circuit 30 is completed from battery through the left-hand winding of relay 323, contact 322 (1) of sequence 320 associated with the register mechanism, conductor 293, over a contact such as 655 closed in a position corresponding to the selected register mechanism, contact 639 (4), right-hand winding of relay 637, contact 655, closed in the consecutive 35 half positions of sequence switch 680, to ground. The contacts such as 656 of sequence switch 680 are arranged so that their circuit-closing positions extend over an angular distance sufficient to insure the closure of the above traced test circuit when 40 contact 655 is in one of its successive half positions, this latter contact being arranged to make only brief closures. Relay 637 attracts its armature and closes a circuit through its left-hand low resistance winding, and the winding of relay 638 to ground in shunt of the right-hand winding of relay 637. The resistance of this circuit, being low, reduces the potential on the conductor 293 such that the register controlling 45 mechanism now tests busy. Relay 638 attracts its armature and opens the circuit just traced for the testing sequence switch 680, so that this sequence switch, upon arriving in its full position, comes to rest. 50 A circuit is also established by relay 638

for sequence switch 620, which may be traced from battery, through the winding of such sequence switch contact 645 (4), front contact and armature of relay 638, contact 654 (4) to ground at sequence switch contact 70 655. Sequence switch 620 moves out of position 4 and into position 5. As the sequence switch 620 passes out of position 4, the bridge across the calling line through the relay 631 and retardation coil 623 is opened at contacts 601 and 602, and in position 5 the calling line is connected over these contacts to the stepping relay 325 of the register set. The circuit of relay 325 may be followed from battery, through the left-hand winding thereof, left-hand contact of relay 301, contact 657 of sequence switch 680, contact 602 (5), trunk conductor 655, thence over the loop of the calling line and returning by way of trunk conductor 654, sequence switch contacts 601 (5), contact 658, right-hand contact of relay 301 through the right-hand winding of relay 325 to ground. 75 80 85

It will be observed that the impulse circuit above traced, extending from the calling subscriber's line through the satellite to the register mechanism at the exchange, comprises a two-conductor metallic circuit that is free from impedances, bridges, battery and ground connections at the satellite, and that no repeating devices are necessary to transfer the impulses sent out at the calling substation from the satellite to the exchange. 90 95 100

At the time the register mechanism shown was selected by sequence switch 680, it will be remembered the relay 323 was energized in series with the relay 637. Relay 323 closes a circuit from battery, through the winding of sequence switch 320 through the right-hand winding of relay 323, front contact and armature to ground. Sequence switch 320 thereupon advances into position 3. On leaving position 2, the original circuit through the left-hand winding of relay 323 is opened at contact 322 so that this relay deenergizes to open the starting circuit of the sequence switch 320 before it can reach position 3. As relay 323 releases its armature and with sequence switch 320 in position 3, a circuit is closed from battery, contact 327 (3) through the winding of relay 326, back contact and armature of relay 323 to ground, causing the energization of relay 326. The apparatus is now in condition for the calling subscriber to send impulses in accordance with the called line designation to position the register mechanism to subsequently control the selective 105 110 115 120 125 operation of the automatic switches.

While the drawings only show a first group selector at the exchange, it is to be understood that there are to be succeeding selector switches as, for example, a final 130

switch in which case three selecting operations are necessary to complete connection to the called line. The register controlling equipment shown has a capacity sufficient 5 to effect five controlling operations, there being five register sequence switches. If desirable the exchange may be of such a size as to necessitate a sufficient number of selector switches to use all of the controlling 10 registers, or, if desirable, a part or all of the registers may be used to control selective switches in a distant exchange in case of an outgoing call. For the purpose of the present description, it will be assumed that 15 the exchange shown in this system is only equipped with a group selector and a final selector, whereby only three selective operations are necessary. In this case the subscriber may dial a series of impulses to set 20 each of the controlling registers, but since the call is one local to a first exchange the last three registers alone are effective to control the operation of the selective switches therein. The type of registers used in this 25 system is one in which the sequence switches are provided with ten positions. Each sequence switch advances to a position corresponding to the number of impulses sent from the subscriber's dial during the positioning period of the registers, and later 30 runs through the remaining positions to its home position to control the operation of the selective switches. It is, therefore, obvious 35 that the number of steps taken by the register while controlling a selective switch is the complement of the number of impulses sent by the calling subscriber. In order that the switches be controlled in accordance with the numerical designations of 40 the called line, it only becomes necessary to arrange the subscriber's sender so that the complement rather than the actual digit itself is sent to the controlling registers. The subscriber's dial is further arranged so that 45 the last interruption of the line of each impulse series is of a longer duration than the others. The reason for this feature will appear hereinafter.

The stepping relay 325 being energized 50 in series with the calling line over the circuit described closes a circuit from ground, over its armature and front contact, armature and front contact of relay 326, contact 330 (3), through the right-hand winding of 55 differential relay 329, armature and back contact of this relay, contact 328 (3), through the winding of the register 100, to battery and ground. A parallel circuit for the left-hand winding of relay 329 is also 60 closed to ground at the armature and contact of relay 325. Both windings being energized the relay 329 does not attract its armature. The register 100, however, energizes and moves out of position 0. As the 65 local contact 101 of this register closes in

the well known manner in the half position between position 0 and position 1 directly to ground, the right-hand winding of differential relay 329 is thereby shunted and said relay attracts its armature. The relay 337 70 is connected in parallel to the register 100 in a circuit through the right-hand winding of differential relay 329 and insures that the register moves fully out of each of its positions before the energizing circuit of 75 such register can be opened by the relay 329. The register 100 under the control of its local contact 101 advances into its first position where it remains. As sequence switch 320 passed out of position 1, the interrupter 333 was connected over sequence contact 332 to the winding of a dialing tone apparatus 324. The calling subscriber hearing a distinctive tone in his receiver knows that he 80 may proceed with the transmission of impulses. Upon the first interruption of the calling line at the subscriber's dial, relay 325 retracts its armature and opens the circuit of the left-hand winding of relay 329, 85 which consequently becomes deenergized. As the line circuit again closes, the register 100 is energized once more and moves out of position 1. Relay 329 again energizes, the register passes to position 2 and at the 90 next interruption of the line circuit, relay 329 becomes deenergized. This procedure continues the register advancing one position upon each interruption of the line until the first series of impulses have been completed. At each retraction of the armature 95 at relay 325, a momentary circuit is completed over contact 331 (3) for relay 334. This relay, however, being slow to energize 100 does not attract its armature. At the last interruption of the line circuit which, as above noted, is comparatively longer than the proceeding interruptions of the series, the circuit of relay 334 is closed sufficiently long to permit it to energize. A circuit is now completed from battery, through the left-hand winding of relay 323 to ground at the contact and armature of relay 334. Relay 323 in turn closes a circuit to drive sequence switch 320 out of position 3. Before 105 sequence switch 320 can have reached position 5, the line circuit is again closed and relay 334 deenergized to in turn cause the deenergization of relay 323. Sequence switch 320, therefore, comes to rest in position 5. Relay 326 which had its circuit 110 opened at the back contact of relay 323 deenergized while sequence switch 320 was passing from position 3 to position 5. In passing through position 4, a circuit is closed over contact 328 (4), contact and right-hand armature and right-hand winding of relay 329, and contact 330 (4) to advance 115 the register 100 one step in addition to the position to which it was set by the subscriber's sender.

120

125

130

The control of the stepping relay 325 is now shifted from the register 100 to register 110, and as soon as relay 326 energizes as sequence switch 320 reaches position 5 and relay 323 releases its armature, a circuit is closed from ground, armature and front contact of stepping relay 325, armature and front contact of relay 326, contact 105 of register 100 through the right-hand winding of differential relay 329, armature and contact thereof, sequence switch contact 328 (5) through the winding of the second register to battery and ground. In a manner similar to that described, a parallel circuit is closed over the left-hand winding of relay 329 to prevent this relay from attracting its armature. The register 110 moves out of position 0 where it short circuits the right winding of differential relay 329 to permit the energization of this relay. When the subscriber operates his dial to send the second series of impulses, the first interruption of the line circuit causes the release of relay 325 which in turn permits the deenergization of relay 329. The register 110 advances under the control of its local contact into position 1. For each succeeding interruption of the line circuit register 110 moves forward one position and at the last interruption of the impulse series, relay 334 operates to cause the operation of relay 323, which closes a circuit to drive sequence switch 320 out of position 5. As sequence switch 320 is passing from position 5 to position 8, the line circuit is again closed to cause the energization of relay 325 which thereby permits the release of relays 334 and 323, so that upon coming into position 8, sequence switch 320 will stop. Relay 326 deenergizes as sequence switch 320 leaves position 5, and again energizes as said sequence switch arrives in position 8 in a manner similar to that described in connection with the setting of the first register. As soon as relay 326 is again energized, a circuit is completed from ground, armature and front contact of the stepping relay 325, armature and front contact of relay 326, contact 105, through the right-hand winding of relay 329, armature and contact thereof, sequence switch contact 335 (8) through the winding of the third register sequence switch 120 to battery and ground.

The calling subscriber now manipulates his dial in accordance with the third digit of the desired number, and register 120 is advanced to its proper position under the control of the stepping relay 325. At the termination of the third series of impulses relay 334 is again energized, and sequence switch 320 moves from position 8 into position 10. A circuit is now closed from ground, armature and front contact of relay 325, armature and front contact of relay 326, contact 105 through the right-hand

winding of differential relay 329, armature and contact thereof, contact 335 (10) through the winding of the register 130, to battery and ground.

The interruption of the line circuit during the sending of the fourth series of impulses causes the advance of register 130 under the control of stepping relay 325. At the end of this series of impulses, sequence switch 320 is energized in the manner already described and moves from position 10 into position 12. The circuit for the control of the last register 140 is now completed from ground, armature and front contact of relay 325, armature and front contact of relay 326, contact 105 to the right-hand winding of relay 329, armature and contact thereof, sequence switch contact 336 (12) through the winding of the register 140 to battery and ground. As the calling subscriber manipulates his dial in accordance with the final digit, the stepping relay operates as above described to control the positioning of the register 140. Upon the last relatively long interruption of the line in the final impulse series, relay 334 is energized and sequence switch 320 moves from position 12 into position 14. As the line circuit is again closed, relays 334 and 323 deenergize and relay 326 also becomes deenergized as soon as sequence switch 320 leaves position 12 to open its contact 327.

When the first three series of impulses have been transmitted, and the corresponding registers 100, 110 and 120 moved to their set positions, whereafter the sequence switch 320 immediately passes out of position 8, as described, a circuit is established to move the outgoing sequence switch 350 of the register set of the register mechanism out of its first position. This circuit extends from battery, through the winding of said sequence switch, contact 352 (1), contact 103 of register 100, to ground at contact 338 of register 320, sequence switch 350 which controls the restoration of the registers starts from position 1 and moves into position 3. As sequence switch 350 passes through position 1½, a circuit is established from battery, through the winding of relays 382 and 383, contact 106 of register 100, contact 116 of register 110, contact 127 of register 120, contact 372 of register 350, to ground. Relays 382 and 383 energize and the following holding circuit is completed: battery, through the windings of these relays, contacts and left-hand armature of relay 383, sequence switch contact 369 closed in positions 2 to 12, to ground. Relay 382, by attracting its armatures, closes a circuit so that sequence switch 350 continues to move through positions 3 and 4 and into position 5. This circuit is traceable from battery through the winding of sequence switch 130

350, left-hand armature and contact of relay 382, contact 380, closed in positions 2 to 4, to ground at the right-hand armature of relay 382. Relay 357 is energized to hold the fundamental circuit open while sequence switch 350 is passing through positions 2 to 4 over a circuit from battery, through the winding of this relay, contact 380 to ground at the right-hand armature 10 of relay 382.

As sequence switch 350 reaches position 2, a circuit is closed from battery through the right-hand winding of differential relay 359, contact and armature of relay 355, 15 sequence switch contact 354, to ground at contact 381. The relay 359 energizes in this circuit.

Upon reaching position 5 the fundamental circuit for controlling the selective operation of the group selector shown in Fig. 2 is established. This circuit may be traced from battery, through the winding of relay 622, contact 630 (5) of sequence switch 620, conductor 296, armature and contact of relay 357, through the winding of the stepping relay 355, contact 380 (5) of sequence switch 350, to ground at the right-hand armature of relay 382. Stepping relay 355, energizing, opens the circuit just traced for relay 359 to permit the same to deenergize. The relay 622 energizes in the fundamental circuit and closes a circuit from ground, armature and back contact of relay 631, armature and front contact of relay 622, contact 645 (5) through the winding of sequence switch 620 to battery and ground. Sequence switch 620 moves out of position 5 and into position 6. A circuit is now completed from battery through the winding of trip spindle magnet 648, contact 649 (6), front contact and armature of relay 622, back contact and armature of relay 631 to ground. The magnet 648 energizes and the trip spindle rotates, closing in the well-known manner a set of interrupter contacts 659 as the trip spindle approaches each successive brush tripping position.

The stepping relay 355 also energizes in the fundamental circuit in series with relay 622. When the tripping spindle approaches the first brush tripping position, the interrupter contact 659 closes a circuit directly to ground for relay 622 over sequence switch contact 632 (6). The stepping relay 355 is shunted by this path to ground, and releasing its armature closes a circuit from ground, contact 381, contact 354 (5), armature and contact of the stepping relay 355 through the left-hand winding of differential relay 359, armature and contact of this relay, contact 366 (5), contact 122 of register 120, through the winding of such register to battery and ground. A parallel circuit is also closed for the right-hand winding of the dif-

ferential relay 359 to ground at the contact 381. Both windings of relay 359 being simultaneously energized, it does not attract its armature. The register 120, however, which controls the operation of the group selector shown in Fig. 2, energizes and moves out of the position to which it was set by the calling subscriber's dial. Midway between positions the local contact 121 of register 120, being connected directly to ground, short circuits the left-hand winding of differential relay 359 which thereupon operates. The register 120 under the control of its local contact advances to the next position. As the tripping spindle reaches its first position, the interrupter contact 659 is opened, relay 355 is again energized, and opening the circuit of the right-hand winding of relay 359, permits the latter to release its armature. On approach of the tripping spindle to its next position, the interrupter 659 is closed and the stepping relay 355 de-energizes. The register 120 is energized as before in series with the left-hand winding of relay 359, and begins to move to its next position. When the local contact 121 closes, relay 359 energizes as described, opening the starting circuit of the register 120, and the register now advances into position under control of its local contact 121. When the tripping spindle has reached its second position the stepping relay 355 again energizes and the differential relay 359 in turn deenergizes. This operation continues, the register 120 advancing one position for each de-energization of the stepping relay 355, until it reaches its home position 0. At the next deenergization of relay 355, after register 120 has arrived in position 0, a circuit is completed for relay 357 from battery, to the winding of this relay, sequence switch contact 364 (5), contact 124 (0) of register 120, contact 366 (5), contact and armature and left-hand winding of relay 359, contact and armature of relay 355, sequence switch contact 354 (5), to ground at contact 381. A parallel circuit is also completed from battery, through the winding of sequence switch 350, left-hand armature and contact of relay 382, contact 354 (5), contact 124 (0), contact 366 (5), contact and armature and left-hand winding of relay 359, contact and armature of relay 355, contact 354 (5), to ground at contact 381. The sequence switch 350 moves out of position 5 and into position 6. Relay 357, energizing, opens the fundamental circuit to prevent any further operation of the register 120. As soon as the interrupter contact 659 opens, the fundamental circuit being broken at the register set, relay 622 deenergizes and closes a circuit from battery, through the winding of sequence switch 620, contact 646 (6), back contact and armature of relay 622, to ground at the back contact and armature of relay 631. Sequence 130

switch 620 moves from position 6 into position 7. In position 7 of sequence switch 620 the relay 622 is energized in a circuit from battery, through the winding of this relay, 5 winding of relay 653, sequence switch contact 639, contact 656, conductor 293, back contact and armature of relay 339, contact 340 (4 to 15) of sequence switch 320, to ground. Relay 653 also energizes in this circuit. A 10 circuit is now established for the brush carriage power magnet 644 of the group selector. This circuit is traceable from battery, through the winding of such power magnet, contact 641 (7), back contact and armature of 15 relay 638, front contact and armature of relay 622, back contact and armature of relay 631, to ground.

The brush carriage of the group selector is rotated in the well-known manner, the set 20 of brushes selected by the tripping spindle are tripped and moves over the terminals such as terminals 690, 691 and 692 of the level of trunks leading to the proper group of final selector switches. When the test brush of the 25 group selector is advanced into engagement with the test terminal 692 of an idle trunk circuit, a selectable potential is found thereon and test relay 637 energizes in a circuit over contact 640 (7) through the right-hand high resistance winding of relay 637, 30 back contact and armature of relay 624, contact 654 (7), contact 655, to ground. The relay 637 energizes and closes a low resistance circuit through its left-hand winding and the winding of relay 638 to ground, 35 thus reducing the potential on terminal 692 in the well-known manner. When the brushes of the group selector are accurately centered on terminals 690, 691, 692, the interrupter brush 652 removes the short-circuit from around relay 638 and this relay, 40 by energizing, opens the above traced power circuit for the magnet 644, thus causing the brush carriage to come to rest. Furthermore, the energization of relay 638 closes 45 a circuit from battery, through the winding of sequence switch 620, contact 645 (7 to 8), front contact and armature of relay 638, front contact and armature of relay 622, back contact and armature of relay 631, to 50 ground. Sequence switch 620 moves through position 8 and into position 9. In position 9 of sequence switch 620, the fundamental circuit, comprising the two conductors 55 296 and 297, is extended over sequence switch contacts 630 and 651 to the selected final switch.

When relay 653 energizes in series with 60 relay 622, as sequence switch 620 reaches position 7, it closes a circuit to ground in shunt of the contact and armature of relay 663 to hold the relay 670 in the satellite energized. At the right-hand armature of relay 653, a circuit is completed for the energization of the slow-to-release relay 663.

The function of these two relays will be described hereinafter.

If at the time the group selector completes its hunting operation and seizes a trunk leading to a final selector, the tens and units registers 130 and 140 have been positioned under the control of the stepping circuit from the calling subscriber's line, the sequence switch 320, as above described, will have moved into position 14. The sequence switch 350, which moved into position 6 at the termination of the group selector brush tripping operation, awaits the movement of sequence switch 320 into position 14, provided the latter has not already advanced to such position. A circuit is thereupon completed from battery, through the winding of sequence switch 350, contact 352 (6), contact 341 (14) of sequence switch 320, to ground. Sequence switch 350 leaves position 6 and goes into position 7 in which the fundamental circuit is closed at the register controlling mechanism. The fundamental circuit includes, as is well understood, the line relay of the final selector switch (not shown) and extends over terminal 690, contact 651 (9), conductor 297, right-hand armature and contact of relay 383, contact 385 (7), through the winding of the stepping relay 355, contact and armature of relay 357, conductor 296, sequence switch contact 630 (9), terminal 691 and thence to the final selector switch.

During the rotation of the tripping spindle of the final selector switch, the stepping relay 355 is short circuited in the usual manner, and each time it deenergizes, a circuit is completed from ground, contact 381, contact 354 (7), armature and contact of relay 355, through the left-hand winding of relay 359, armature and contact of this relay, contact 366 (7), contact 132 of the tens register 130, through the winding of register 130, to battery and ground. In the manner above described in connection with the restoration of the register 120, the register 130 passes through one position for each brush tripping position passed over by the tripping spindle of the final selector switch. When register 130 reaches position 0, a circuit is established from battery, through the winding of relay 357, contact 364, (7), contact 134 (0), contact 366 (7), contact and armature and left-hand winding of relay 359, contact and armature of relay 355, contact 354 (7), to ground at contact 381. A parallel circuit is closed at the same time from battery, through the winding of sequence switch 350, left-hand armature and contact of relay 382, contact 364 (7), contact 134 (0), contact 366 (7) to ground as above traced at the contact 381. Relay 357 energizes to open the fundamental circuit while sequence switch 350 advances from position 7 into position 9.

The fundamental circuit remains closed at the register controlling mechanism with sequence switch 350 in position 9 and when, at the final selector, the brush carriage is rotated in the well-known manner to perform the units selection the usual shunting of the stepping relay 355, as the brushes pass over the terminals of each line in the selected level, causes said relay to intermittently release its armature. At each deenergization of relay 355, a circuit is closed from ground, contact 381, contact 354 (9), armature and contact of relay 355, left-hand winding and armature and contact of differential relay 359, contact 367 (9), contact 142 of the units register 140 through the winding of this register to battery and ground. In the manner now already well understood the register 140 moves through one step for each operation of the stepping relay 355 until it reaches position 0. At this time the circuit is closed from battery, through the winding of relay 357, contact 364 (9), contact 144 (0), back contact and armature of relay 374, contact 145 to 0, contact 367 (9), contact and armature and left-hand winding of relay 359, contact and armature of relay 355, contact 354 (9), to ground at contact 381. A circuit is also closed at this time from battery, through the winding of sequence switch 350, left-hand armature and contact of relay 382 and thence to ground at the contact 381 in parallel to the circuit just traced for relay 357. The relay 357 opens the fundamental circuit, whereas sequence switch 350 moves from position 9 into position 12.

In passing through position 10 sequence switch 350 closes a circuit from battery, through the winding of relay 339, contact 368, contact and left-hand armature of relay 383, to ground at contact 369. The relay 339 by attracting its armature opens the circuit hereinbefore traced, which is holding relays 622 and 653 energized. Relay 622 deenergizes and closes a circuit from battery, through the winding of sequence switch 620, contact 646 (9), back contact and armature of relay 622, back contact and armature of relay 631 to ground, whereupon sequence switch 620 moves out of position 9. In position 10 the movement of sequence switch 620 is continued by means of a circuit closed over sequence switch contact 628 and the back contact and armature of relay 627, to ground. Sequence switch 620, therefore, comes to rest in position 11.

When sequence switch contacts 601 and 602 leave position 9, the circuit of the stepping relay 325 is opened, and deenergizing, this relay closes a circuit from ground, over its armature and back contact, contact 348 (14), through the winding of sequence switch 320, to battery, to drive said sequence switch out of position 14 and into position 15. In position 15 of sequence switch 320

the sequence switch 350 is driven into position 13 by means of a circuit closed from battery, through the winding of sequence switch 350, contact 367 (12) and contact 343 (15), to ground. In position 13 of sequence switch 350, the register 100, which, in the case assumed, was not needed since only a group and a final selector were involved in the extension of the call is restored to its normal position. The circuit for driving the register 100 back to position 0 may be traced from battery, through the winding of such register contact 102, contact 361 (13) and contact 343 (15), to ground. On reaching position 0, register 100 completes a circuit from battery, through the winding of sequence switch 350, contact 379 (13), contact 363 (13), contact 104 (0), contact 361 (13) and contact 341 (15) to ground to drive sequence switch 350 into position 14. The second register 110 is now driven back to its normal position to 0 in circuit from battery, through the winding of this register, contact 112, contact 361 (14), to ground at contact 343 (15). When register 110 reaches position 0, a circuit is completed from battery, through the winding of sequence switch 350, contact 379 (14), contact 363 (14), contact 114 (0), contact 361 (14), to ground at contact 343, whereupon sequence switch 350 moves out of position 14. In position 15 sequence switch 350 continues to move by means of a circuit closed from battery, through the winding thereof, contact 379 (15), contact 364 (15), contact 124 of register 120 now in position 0, contact 366 (15), to ground at contact 343. In position 16, sequence switch 350 continues to advance by means of a circuit from battery, through the winding thereof, contact 379 (16), contact 364 (16), contact 134 of register 130 now in position 0, contact 366 (16) and contact 343 to ground. In position 17 a circuit is completed to drive sequence switch 350 into its normal or first position from battery, through the winding of said sequence switch contact 379 (17), contact 364 (17), contact 144 of register 140 now in position 0, back contact and armature of relay 374, contact 145, contact 367 (17) to ground at contact 343. Sequence switch 350 in its normal position, closes a circuit for relay 323 traceable from battery, through the left-hand winding of said relay, sequence switch contact 322 (15) and sequence switch contact 369 (1), to ground. Relay 323 attracting its armature closes a circuit over its right-hand winding to drive sequence switch 320 out of position 15. In position 17 of sequence switch 320 a circuit is closed for relay 334 over contact 331 (17), back contact and armature of relay 326, to ground at sequence switch contact 340 (17). Relay 334 energizes and closes a circuit for the left-hand winding of relay 323 and thereby maintains the energ- 130

gization of this latter relay so that sequence switch 320 passes over position 17 and comes to rest in its normal or first position. The register controlling mechanism is now completely restored to its normal position and is ready to be seized for controlling other selective operations.

Returning now to the point where relay 653 was deenergized at the time relay 339 of the controlling mechanism was energized, a description will be given of the operations produced at the outgoing end of the trunk circuit in the satellite by the operation of relay 653. On releasing its left-hand armature relay 653 opens the circuit formerly traced for maintaining the energization of relay 670 in the satellite. Relay 663, which is energized at this time over a circuit including the right-hand armature of relay 653 maintains its armature attracted for a definite interval of time after the release of relay 653 by reason of its slow-to-release character. Therefore, for the period of time that relay 663 requires to release its armature, the circuit of relay 670 is held open. Relay 670 on releasing its armature opens the circuit of relay 671 which controls the energizing circuits of both relays 676 and 673. The relay 671 is so constructed that it will not release its armature until after the expiration of a period greater than that required for relay 663 to deenergize. Relays 676 and 673 are consequently held energized during the time relay 663 is releasing its armature. When relay 670 deenergizes it closes a circuit from battery, over its armature and back contact, through the left-hand winding of relay 678, front contact and left-hand armature of relay 676, to ground at the front contact and right-hand armature of relay 673. Relay 678 by attracting its armature, closes a locking circuit for itself in series with relay 679, traceable from battery, through the winding of relay 677, winding of relay 679, right-hand winding, front contact and armature of relay 678, front contact and right-hand armature of relay 673, to ground. Relay 679 completes a circuit from battery, through the winding of relay 668, right-hand armature and contact of relay 679, over the loop of the calling line and thence to ground by way of the left-hand armature and contact of relay 679 and the winding of retardation coil 694. The supply of talking battery for the calling subscriber's line is thus connected across the trunk circuit in the satellite. The relay 678 on attracting its armature opens the circuit hereinbefore traced for relay 635 which releases its armatures and closes the talking conductors 654 and 655 of the outgoing end of the trunk circuit through the coil 660. Relay 631 is now energized in a circuit to ground 65 through the retardation coil 623 in series

with coil 660. As soon as the slow-to-release relay 663 retracts its armature the original energizing circuit of relay 670 is again closed and this relay operates to complete the temporarily opened circuit of relay 671, whereby relays 671, 676 and 673 are maintained energized.

The final selector having been moved in the well-known manner under the control of the register mechanism to the terminals of the called line, such as line 650, the usual test is made, ringing current applied and the changeover operations in the circuits of the final selector switch effected. When the called subscriber answers relay 627 at the group selector is energized in series with the called line in a circuit extending to ground, through retardation coil 626 and the front contact and armature of relay 631. Relay 627 energizing closes a circuit from ground over its armature and front contact, sequence switch contact 645 (11), through the winding of sequence switch 620 to battery, whereupon sequence switch 620 moves into position 12 which is the talking position thereof. The calling and called subscribers may now proceed with the conversation.

At the end of the conversation when the calling subscriber replaces his receiver to the switchhook, relay 631 deenergizes and closes a circuit from ground, over its armature and back contact, armature and back contact of relay 622, sequence switch contact 646 (12), through the winding of sequence switch 620 to battery, to drive said sequence switch out of position 12 and through position 13 into position 17. In this position the brush carriage of the group selector is restored to normal position by means of a circuit from battery, through the winding of the power magnet 644, contact 641 (17), back contact and armature of relay 638, contact 654 (17), to ground at the contact 655. When the brush carriage reaches its normal position relay 638 is energized in a circuit from ground, through the winding thereof, interrupter 652 and its home contact, sequence switch contact 642 (17), to battery and ground. Relay 638 energizes and opens the circuit of the power magnet 644 causing the brush carriage to cease rotating, and also closes a circuit from battery, through the winding of sequence switch 620, contact 645 (17), front contact and armature of relay 638, contact 654 (17) to ground at contact 655. The sequence switch 620 thereupon moves into position 18 where a circuit is closed from battery, through the winding of relay 627 and sequence switch contact 629, to ground. Relay 627 energizes and closes a circuit from ground, over the armature and front contact thereof, sequence switch contact 645 (18), through the winding of sequence

switch 620 to battery, to drive said sequence switch out of position 18 and into its normal position 1. The group selector is now completely restored to its normal position. 5 The restoration of the final and other succeeding selector switches will take place in any well-known manner.

When sequence switch 620 leaves position 13 during the release of the connection, the 10 original circuit of the relays 664 and 670 is opened at sequence switch contact 636, and a new circuit is immediately closed over said contact including a source of current 659 and the armature and back contact of relay 15 624. The battery 659 is of such polarity that the current flowing in the circuit of relay 664 is now sufficient to energize the same. Relay 664 attracts its armature and connects a 20 source of metering battery in series with the meter magnet 608 which operates to charge the call. The circuit of relay 673, being opened at the back contact of relay 664, this relay deenergizes whereupon the relays 677, 679 and 678 are permitted to release their 25 armatures. When sequence switch 620 subsequently passes out of position 16, sequence switch contact 636 is opened and relays 664 and 670 are released. The circuits of relays 671 and 676 are now opened, and these relays 30 deenergize. The cut-off relay 607 also deenergizes at the time the circuit of relay 673 is opened at the back contact of the relay 664. The apparatus in the satellite is now 35 restored to its normal position ready to be taken for subsequent calls.

If the called line is found to be busy or if the called subscriber does not answer, relay 627 does not energize and consequently the sequence switch 620 stops in position 11. 40 When the calling subscriber hangs up his receiver and relay 668 deenergizes, thus causing the release of relay 631, a circuit is closed from ground, over the armature and back contact of relay 631, armature and back 45 contact of relay 622, contact 646 (11), through the left-hand winding of relay 624, to battery and ground. Relay 624 operates and closes a circuit from battery, through the winding of sequence switch 620, right-hand winding, front contact and armature 50 of relay 624, contact 654 (11), to ground at the contact 655. Sequence switch 620 moves over positions 12 and 13 and comes to rest in position 17. In this instance since the 55 relay 624 is energized, the battery 659 is not applied to conductor 603 to operate the marginal relay 664 as sequence switch contact moves over positions 14 to 16, and as a result the meter 608 is not operated to charge the 60 call. When sequence switch contact 636 leaves position 13, relay 670 is deenergized and after a sufficient interval of time the slow relay 671 releases its armature and restores to normal the circuits of the finder 65 switches in the satellite.

In position 17 of sequence switch 620, the restoration of the group selector takes place in the manner above described.

What is claimed is:

1. In a telephone exchange system, a subscriber's line, a switching station, a trunk line outgoing therefrom, a distant switching station in which said trunk terminates, switches at said first station for connecting the subscriber's line to said trunk, switches 70 at said distant station for extending said trunk line, an impulse circuit including the talking conductors of said trunk which is free from impedances at the first station for transmitting impulses from the subscriber's line to the distant station to control the switches therein, a source of talking current associated with the talking conductors of said trunk circuit at the first station, and means for rendering said source of current 75 effective for conversation.

2. In a telephone exchange system, a subscriber's line, a switching station, a trunk line outgoing therefrom, a distant switching station in which said trunk terminates, switches at said first station for connecting the subscriber's line to said trunk, switches 90 at said distant station for extending said trunk line, an impulse circuit including the talking conductors of said trunk which is free from impedances, bridges, ground and other connections at the first station for transmitting impulses from the subscriber's line to said distant station to control the switches therein, a source of talking current 95 connected to the trunk line at said first station, and means for rendering said source of current effective for conversation.

3. In a telephone exchange system, a subscriber's line, a switching station, a distant switching station, a trunk circuit outgoing from said first station to the distant station, switches at the first station for connecting the subscriber's line to said trunk circuit, switches at the distant station for extending said trunk circuit, condensers and a source 105 of talking battery connected in the trunk circuit at the first station, means for establishing an impulse circuit which is free from impedances, bridges, ground and other connections at the first station and which includes the talking conductors of said trunk circuit for transmitting impulses from the subscriber's line to the distant station to control the switches therein, said condensers 110 and talking battery being inoperative during the transmission of impulses, and means for disabling said impulse circuit and for rendering said condensers and talking battery effective for conversation.

4. In a telephone system, a subscriber's line, a switching station, a trunk line outgoing therefrom, a distant switching station in which said trunk terminates, switches at said first station for connecting the subscriber's 125 line to the trunk, switches at the distant station for extending the trunk line, an impulse circuit including the talking conductors of the trunk which is free from impedances, 130

line to said trunk, switches at said distant station for extending said trunk line, means for transmitting impulses from the subscriber's line over said trunk line to the 5 distant station to control the switches therein, a source of talking current at said first station connected to said trunk line, means for opening one of the conductors of said trunk line for a predetermined time interval, and means responsive to such opening for rendering said source of current effective for conversation.

5. In a telephone system, a subscriber's line, a switching station, a trunk line outgoing therefrom, a distant switching station in which said trunk terminates, switches at said first station for connecting the subscriber's line to said trunk, switches at said distant station for extending said trunk 10 line, a controlling mechanism for controlling the operation of the switches in said distant station, means for transmitting impulses from the subscriber's line over said trunk line to the distant station to set said 15 controlling mechanism, a source of talking current at said first station associated with said trunk line, means operated by said controlling mechanism at the completion of its operation for opening one of the 20 conductors of said trunk line for a predetermined interval of time, and means responsive to such opening for rendering said source of current effective for conversation.

6. In a telephone system, a subscriber's line, a satellite, a trunk line outgoing therefrom, an exchange to which said trunk line leads, switches at said satellite for connecting the subscriber's line to said trunk, switches at the exchange for extending said 25 trunk, a set of registers for controlling the operation of the switches in the exchange, means for transmitting impulses from the subscriber's line over said trunk line to the exchange to set said registers, a source of 30 talking current in the satellite associated with said trunk line, means operated by said registers upon the completion of their controlling operation for opening one of the conductors of said trunk line for a predetermined 35 interval of time, and means responsive to such opening for rendering said source of current effective for conversation.

7. In a telephone system, a subscriber's line, a switching station, a three-conductor trunk line outgoing therefrom, a distant switching station to which said trunk line leads, switches at said first station for connecting the subscriber's line to said trunk, switches at the distant station for extending 40 said trunk, means for transmitting impulses from the subscriber's line directly to the distant station over two conductors of said trunk line to control the operation of the switches therein, a source of talking current 45 at said first station associated with said

trunk line, a circuit including the third conductor of said trunk line, means for changing the condition of said circuit for a definite interval of time, and means responsive to such change for rendering said 70 source of current effective for conversation.

8. In a telephone system, a subscriber's line, a satellite, a three-conductor trunk line outgoing therefrom, a distant exchange in which said trunk terminates, switches at the 75 satellite for connecting the subscriber's line to said trunk, switches at the exchange for extending said trunk, a register controlling mechanism arranged to be set in accordance with numerical designations to control the 80 operation of the switches in said exchange, means for transmitting impulses from the subscriber's line over two conductors of said trunk line to the exchange to set said register controlling mechanism, a source of talking current in the satellite associated with said trunk line, a circuit including the third conductor of said trunk line, means operated by said register controlling mechanism upon the completion of its controlling 85 operation for opening said circuit for a definite interval of time, and means responsive to such opening for rendering said 90 source of current effective for conversation.

9. In a telephone system, a subscriber's 95 line, an automatic switch, a three-conductor connecting circuit, means for operating said switch to connect the subscriber's line to said connecting circuit, a second automatic switch in which said connecting circuit terminates, a controlling mechanism arranged to be set in accordance with numerical 100 designations for controlling the operation of said second automatic switch, means for transmitting impulses from the subscriber's line over two conductors of said connecting circuit to set said controlling mechanism, a source of talking current at said first automatic switch associated with the connecting 105 circuit, a controlling circuit including the third conductor of said connecting circuit, means operated by said controlling mechanism upon the completion of its operation for changing the condition of said controlling circuit for a definite interval of time, 110 means responsive to such change for rendering said source of current effective for conversation, and means operated when the condition of said controlling circuit is changed for a longer interval of time to release 115 said first automatic switch.

10. In a telephone system, a subscriber's line, a satellite, a three-conductor trunk line outgoing therefrom, a distant exchange in which said trunk line terminates, automatic 120 switches in said satellite for connecting the subscriber's line to the trunk line, automatic switches in the exchange for extending said trunk line, registers for controlling 125 the operation of said automatic switches in 130

the exchange, means for transmitting impulses from the subscriber's line to the exchange over two conductors of said trunk line to set said registers, a source of talking current in the satellite associated with said trunk line, a controlling circuit including the third conductor of said trunk line, means operated upon the completion of the operation of said registers for opening said controlling circuit for a definite interval of time, means responsive to such opening for rendering said source of current effective for conversation, and means responsive to the opening of said controlling circuit for a longer interval of time for releasing the automatic switches in said satellite.

11. In a telephone system, a subscriber's line, a trunk line, an automatic switch for connecting the subscriber's line to one end of said trunk, a second automatic switch at the other end of said trunk, an impulse circuit including the talking conductors of said trunk which is free from impedances, bridges, ground and other connections at said first switch for transmitting impulses from the subscriber's line to operate said second switch, a source of talking current associated with the trunk line at said first switch, and means for rendering said source of current effective for conversation.

12. In a telephone system, a subscriber's line, a trunk line, an automatic switch for connecting the subscriber's line to one end of said trunk, a second automatic switch at the other end of said trunk, an impulse circuit including the talking conductors of said trunk which is free from impedances, bridges, ground and other connections at said first switch for transmitting impulses from the subscriber's line to operate said second switch, a source of talking current associated with the trunk line at said first switch, and means controlled over said trunk line for rendering said source of current effective for conversation.

13. In a telephone system, a subscriber's line, a trunk line, an automatic switch for

connecting the subscriber's line to one end of said trunk, a second automatic switch at the other end of said trunk, an impulse circuit including the talking conductors of said trunk which is free from impedances, bridges, ground and other connections at said first switch for transmitting impulses from the subscriber's line to operate said second switch, a source of talking current associated with the trunk line at said first switch, means for changing the condition of said trunk line for a predetermined interval of time, and means responsive to said change for rendering said source of current effective for conversation.

14. In a telephone system, a subscriber's line, a trunk line, an automatic switch for connecting the subscriber's line to one end of said trunk, a second automatic switch at the other end of said trunk, means for sending impulses from the subscriber's line over said trunk, means responsive to such impulses for controlling said second switch to extend the trunk line, a source of talking current at said first switch, means for changing temporarily the condition of said trunk line, and means responsive to said change of condition for rendering said source of current effective for conversation.

15. In a telephone system, a subscriber's line, a trunk line, an automatic switch for connecting the subscriber's line to one end of said trunk line, a second automatic switch at the other end of said trunk, means for sending impulses from the subscriber's line over said trunk, means responsive to such impulses for controlling said second switch to extend the trunk line, a source of talking current at said first switch, a timing device requiring a predetermined interval of time for completing its operation, and means controlled by said device for rendering said source of current effective for conversation.

In witness whereof, I hereunto subscribe my name this 15th day of May A. D., 1919.

LIPA POLINKOWSKY.
